CLAIM

The ornamental design for a notebook computer, as shown and described.

DESCRIPTION

FIG. 1 is a perspective view of a notebook computer showing our new design in a first open configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof shown within an alternative broken line environment of use with a stylus inserted;

FIG. 9 is a perspective view of the notebook computer in a closed configuration;

FIG. 10 is another perspective view thereof shown within an alternative broken line environment of use with a stylus inserted;

FIG. 11 is a perspective view of the notebook computer in a second open configuration;

FIG. 12 is another perspective view thereof shown within an alternative broken line environment of use with a stylus inserted;

FIG. 13 is a perspective view of the notebook computer in a third open configuration;

FIG. 14 is another perspective view thereof shown within an alternative broken line environment of use with a stylus inserted;

FIG. 15 is a top perspective view of the notebook computer shown in FIG. 13;

FIG. 16 is an enlarged view of the indicated portion of the notebook computer labeled "16" in FIG. 15;

FIG. 17 is another top perspective view of the notebook computer shown in FIG. 15 shown within an alternative broken line environment of use with a stylus inserted;

FIG. 18 is an enlarged view of the indicated portion of the notebook computer labeled "18" in FIG. 17;

(Continued)

FIG. 19 is a perspective view of the notebook computer in a fourth open configuration; and,

FIG. 20 is another perspective view thereof shown within an alternative broken line environment of use with a stylus inserted.

The dashed broken lines illustrate portions of the notebook computer and form no part of the claimed design. The dot-dash broken lines define the bounds of the claimed design and form no part thereof. The broken line rectangles in FIGS. 15-18 indicating sections of the figures for which enlarged views are provided form no part of the claimed design.
